UNITED STATES PATENT OFFICE.

ABRAHAM BABITCH, OF FLINT, MICHIGAN, ASSIGNOR TO A C SPARK PLUG COMPANY, OF FLINT, MICHIGAN, A COMPANY OF MICHIGAN.

GASOLINE FILTER.

Application filed December 13, 1926. Serial No. 154,506.

This invention relates to strainers or filters, particularly to that type of strainer employed with gasoline supply systems for internal combustion engines.

5 The invention is especially adaptable for use with that type of strainer embodying a dirt receptacle or settling chamber for sand or other foreign matter, often found in commercial gasoline or other combustible fluid, 10 and which must be taken apart at regular intervals, for cleaning or removal of accumulated sediment.

One of the primary objects of the invention is to provide a device which will be efficient in 15 use, economical to manufacture, of few parts and which may be easily and quickly disassembled for cleaning and reassembled with a minimum of effort.

Other incidental objects will appear from 20 the following specification and accompanying drawing, wherein Figure 1 is a vertical sectional view thru a gasoline strainer embodying the present invention. Figure 2 is an elevation of the strainer looking toward 25 the left in Figure 1. Figure 3 is a bottom plan view of the screen or filter element. Figure 4 is a vertical sectional view of a slightly modified form of strainer used with a vacuum fuel supply system.

30 Referring to the drawing, the reference character 1 indicates a dirt receptacle or sediment chamber, preferably of glass or other transparent material, to enable visual ascertainment of dirt accumulation. The open end 35 or top of the receptacle 1 is closed by a cap or head 2, containing the inlet and outlet passageways for the receptacle. An annular downturned flange 3 overhangs the top of the receptacle or bowl 1 and a gasket or pack- 40 ing ring 4 may be provided to seal the joint between the head and receptacle. Clamped between the head and top of the receptacle is the peripheral marginal edge of a filter or strainer element 5, of fine wire mesh screen or 45 cloth, which marginal edge is provided with a metal ring or ferrule 6, having a number of integral downwardly extended spring fingers 7 exerting an outward pressure to frictionally engage the side of the receptacle. A central 50 opening in the screen 5 is also bounded with a metal band or ferrule 8, and thru this opening extends a dependent hollow stem or stud 9, which is slightly tapered downwardly, and has a shoulder or enlargement 10, to bear 55 against the band 8 at the marginal edge of

the central screen opening. This shoulder 10 is located below the top of the receptacle and peripheral edge of the screen, and consequently, the screen is slightly distorted and assumes a conical shape. The resistance of 60 the screen to such distortion and its natural tendency to return to normal shape, places the screen under tension and the abutment of the shoulder 10 and band 8 is rendered leak-proof. The conduit or pipe 11, from a fuel supply tank, communicates with a passage-way 12 in the top of the head 2, leading to the hollow stem 9, thru a valve chamber 13. To control the liquid flow, a valve stem 14, having screw threaded engagement in a central 70 opening in the fitting 15, screw threaded into the fitting 15^a, in turn threaded into the mouth of the valve chamber 13, carries two enlargements or valve heads 14^a and 14^b. Figure 1 illustrates the adjustment of the stem 14 75 to closed position, when the enlargement or valve head 14^b seats against a shoulder formed by a communicating opening between the valve chamber 13 and the dependent hollow stem 9. In open position, the stem is 80 turned back until the enlargement 14^a contacts the end of the double fitting, thereby serving to seal the fitting against leakage, while the strainer is in use. The open bottom of the hollow stem is plugged by the disc 9^a, 85 and the liquid enters the receptacle thru lateral ports 16, whereby the force of the stream is deflected and no agitation or disturbance of sediment lying on the bottom of the receptacle occurs. Liquid admitted by the inlet 90 flows upward thru the screen, the dirt being precipitated to the bottom of the receptacle, and leaves thru the port 17 into the passage-way 18 and conduit 19, leading to the engine carburetor.

95 It will be apparent that the construction permits the straining and continued collection of sediment, even though the receptacle is almost completely filled, and that the action and efficiency of the strainer is uniform throughout, until substantially the maximum capacity of the receptacle is accumulated.

Pivoted in the head 2 is the swinging bail 20, which passes thru an eye 21 of a screw threaded stud 22, the eye being firmly held 105 by a staking or upsetting operation on a flattened portion of the bail to maintain the stud in an upright position. A knurled nut 23 has threaded engagement on the stud, to move the cup shaped stamping 24 into and 110

out of engagement with the bottom of the receptacle 1.

To remove the dirt receptacle, the nut 23 is screwed down, allowing the stamping to fall and the bail may be swung to one side. Upon disengaging the receptacle from the head, the spring fingers 7 carry the screen along with the receptacle, and the screen may be lifted with the fingers for access to the dirt. After removal of the dirt, the screen is again placed over the top of the receptacle and the spring fingers serve to properly position the screen on the top of the receptacle for the attachment. The stem 9 being tapered, there will be no tendency for the inside marginal edge of the screen to cling or stick to the stem, offering no difficulty to the engagement and disengagement of the parts.

In Figure 4 is illustrated a strainer of the same general type applied to a vacuum fuel supply system. In this instance the supply conduit 11 is connected directly to the inlet stem 9, and the outlet passageway 18 leads to the receiving end of the vacuum tank 25. The passageway 18 extends thru the arm 26, having a terminal eye 27, thru which projects the fastening stud or bolt 28, having a passageway leading to the interior of the vacuum tank. The construction and operation is otherwise as before described.

While the invention has been described more or less specifically, it is to be understood that such obvious modifications may be made as come within the scope of the appended claims.

Having described the invention, I claim:

1. In a strainer, the combination of a dirt receptacle, a cap detachably engageable therewith, having an inlet and an outlet communicating with the receptacle, and a screen separating the inlet and outlet, detachably connected with and removably carried by the receptacle, into and out of clamped engagement between the top of the receptacle and cap.

2. In a strainer, the combination of a dirt receptacle, a cap detachably engageable therewith, having an inlet and an outlet communicating with the receptacle, and a screen separating the inlet and outlet, with its peripheral marginal edge clamped between the receptacle and cap and having a detachable connection with the receptacle, consisting of a portion in frictional contact with the receptacle whereby the screen is carried with the receptacle into and out of engagement with the cap.

3. In a strainer, the combination of a dirt receptacle, a cap detachably engageable therewith, having an inlet and an outlet communicating with the receptacle, and a screen separating the inlet and outlet, with its marginal edge held between the receptacle and cap, and having dependent spring fingers frictionally engaging the side of the recep-

tacle whereby the screen is carried by the receptacle as a unit upon detachment of the receptacle from the cap.

4. In a strainer, the combination of a dirt receptacle, a cap detachably engageable therewith, having an inlet and an outlet communicating with the receptacle, a screen separating the inlet and outlet having its peripheral edges clamped between the top of the receptacle and the cap, a binder element for said peripheral edges having dependent integral spring fingers engageable with the walls of the receptacle to detachably secure the screen on the receptacle and a dependent hollow tapered stem on said cap, slideable thru an opening in the screen to afford said inlet communication and having a shoulder located below the top of the receptacle, against which the inner marginal edge of the screen opening has tensioned contacting abutment.

5. In a strainer, the combination of a dirt receptacle, a cap detachably engageable therewith, having an inlet and an outlet communicating with the receptacle, a screen separating the inlet and outlet having its peripheral edges clamped between the top of the receptacle and the cap, a binder element for said peripheral edges having dependent integral spring fingers engageable with the walls of the receptacle to detachably secure the screen on the receptacle and a dependent hollow stem on said cap, slideable thru an opening in the screen to constitute said inlet communication, said stem having an exterior taper to facilitate its sliding engagement with said screen opening.

6. In a strainer, the combination of a dirt receptacle, a cap detachably engageable therewith, having an inlet and an outlet communicating with the receptacle, a screen separating the inlet and outlet, having its peripheral edges held between the top of the receptacle and said cap, means to detachably connect the screen with the receptacle for removal from the cap as a unit, and a dependent hollow stem on said cap projecting thru and beyond said screen and having a lateral opening constituting said inlet, located adjacent the top of the receptacle.

7. In a strainer, the combination of a head having inlet and outlet openings, a screen interposed between said openings, a receptacle for matter strained by said screen, and means to detachably engage the receptacle with the head, including a swinging bail pivoted to said head, a screw threaded stud having a terminal eye through which the bail extends, an adjustable nut thereon, and a spacer moved into and out of engagement with the bottom of the receptacle upon adjustment of said nut.

8. The combination with two members to be detachably connected to each other, of a swinging bail pivotally carried by one of the members, a screw threaded stud having a ter-

5 minal eye through which the bail extends, the material of which is upset about a flattened portion of the bail to form a rigid connection, a nut adjustably engageable with the stud and a spacer moved by the adjustment of said nut into and out of engagement with the other of said members.

9. A strainer screen, adapted to have its peripheral edges clamped between two members detachably connected with each other, characterized by dependent spring fingers carried by the screen for frictional engagement with one of said members, to detachably secure the screen thereto so as to be carried thereby when the members are detached one from another.

10. A strainer of the class described, including a head having an inlet and an outlet therein, and a unit detachably secured there-

to including a dirt receptacle with which said inlet and outlet communicate, and a screen element removably secured to the receptacle and adapted to be clamped between the receptacle and head and to separate the inlet and outlet.

11. A strainer of the class described, including a head having an inlet and an outlet therein, a dirt receptacle detachably connected to the head with which the inlet and outlet communicate, a strainer element adapted to be clamped between the receptacle and cap to separate said inlet and outlet, and means to detachably connect the strainer element and receptacle for removal from the head as a unit.
